TROUSERS CONSTRUCTION

Rudolf Hirschfeld, New York, N. Y.

Application September 11, 1936, Serial No. 100,229

2 Claims. (Cl. 2—235)

My present invention relates generally to garments, and has particular reference to a trousers construction.

My invention is directed primarily toward the improvement of trousers garments intended to be worn by women and generally referred to in the art by the term "slacks". For the purpose of explaining the invention and depicting its features, the invention is herein illustrated and described as it is applied to a pair of lady's slacks. It will be understood, however, that from certain aspects the invention is not restricted to this specific type of garment.

In the conventional women's trousers construction, the side seams terminate well below the waistline, thereby leaving a slit or opening or V-shaped notch at the top which is intended to facilitate the passage of the garment over the hips of the wearer. When the garment is worn, it is necessary in some way to provide for the sealing of this slit or notch, and it has heretofore been the usual practice to provide either a series of buttons or snap fasteners or the like, or to employ some sort of hookless fastener.

The main object of the present invention is to provide a construction which eliminates the necessity for the usual series of buttons or other closure means by means of which the side slits or notches are sealed. I accomplish this desirable result by a novel structural arrangement of parts whereby the major portion of the slit or notch is adapted to serve as an opening for a pocket.

My present improved construction is characterized by the provision of a means for releasably closing the side notch only at the waistline, and by a unique association with the edges of the notch of a pocket construction of novel character. More particularly, the pocket consists of superposed front and rear walls whose outer edges are, respectively, secured to the front and rear edges of the side notch. In order that the primary function of the notch be not impaired, it is a feature of my invention to leave the front and rear pocket walls disconnected along their top edges.

I achieve the foregoing objects, and such other objects as may hereinafter appear or be pointed out, in the manner illustratively exemplified in the accompanying drawings, wherein—

Figure 1 is a perspective view of a pair of slacks constructed in accordance with the present invention and shown in position on the body of a wearer;

Figure 2 is a perspective view of the upper por-

tion of the trousers construction by itself, showing the parts in the closed relationship;

Figure 3 is a view similar to Figure 2, with the rear portion of the trousers construction broken away and showing one of the side notches in open condition;

Figure 4 is a view similar to Figures 2 and 3, showing the waistband in completely opened relationship; and

Figure 5 is a diagrammatic cross-sectional view taken substantially along the line 5—5 of Figure 3.

The slacks which I have illustrated have the usual leg portions 10, the side seams 11, and the waistband 12 which is continuous across the front, 15 thereby providing a flyless front. The portion 13, lying between the crotch and the waistband proper, will hereinafter be referred to as "the waistband portion". It will be observed that the waistband portion has what may be termed a "hip 20 section", and that the waistband proper is of smaller size than the hip section.

In accordance with usual practice, the trousers consists of front and rear portions which are held together by means of the side seams 11. The latter terminate short of the waistband, e. g., at approximately the point 14, thereby leaving the front and rear portions of the trousers construction in disconnected relationship. There is thus provided above each side seam a V-shaped notch 25 which is shown most clearly in Figure 3, this notch permitting the garment to be passed over the hips of the wearer when it is to be applied or removed. In Figure 3, the front edge of the notch is designated by the reference numeral 15, 30 and the rear edge by the reference numeral 16.

In accordance with my invention, means are provided for releasably closing the notch at the waistline, and I have illustratively shown a pair of buttonholes 17 at the extremity of the front 40 portion of the waistband, these buttonholes cooperating with a pair of buttons 18 provided at the corresponding extremity of the rear portion of the waistband. It will be understood that this arrangement is preferably provided in association 45 with each notch, i. e., at each side of the garment; and in the garment illustrated in the accompanying drawings, the construction at each side is symmetrical with the construction at the opposite side.

The buttons 18, or their equivalents, are obviously inadequate to seal the major portion of the notch. In accordance with my invention, this result is accomplished by the provision of a pocket which consists of the superposed front and rear

50

55

walls 19 and 20, respectively. These pocket walls are connected along their inner edges 21 and along the bottom edges 22, but they are disconnected along the top edges 23 and along the outer edges. The top edges of the pocket walls are spaced downwardly appreciably below the upper edge of the waistband 12 for concealment thereby. The outer edges are permanently secured, preferably by stitches such as those shown at 10 24 and 25, to the front and rear edges of the notch, respectively.

The present construction is completed by the provision of a button 26, or its equivalent, on the front portion of the waistband 12; and the 15 provision of a complementary buttonhole 27, or its equivalent, at the inner upper corner of the pocket. This permits the inner upper portion of the pocket to be releasably secured to the front trousers portion, as shown in Figures 2 and 3. 20 Thus the pockets extend forwardly approximately to the middle of the front where they are secured by the buttons 26, giving added support and more reinforcement to the trousers.

When a person desires to step into the present 25 garment, she first opens the waistband portion, as shown in Figure 4. This permits the notch at each side of the garment to fulfill its primary function, viz., to enlarge the waistband proper and to permit the garment to pass over the hips of 30 the wearer. After the slacks are on, the next procedure is to apply the buttonholes 27 to the corresponding buttons 26, respectively; and the final procedure is to engage the buttonholes 17 with the buttons 18, thereby securing the garment 35 in position, as shown in Figure 1.

While the buttons 18 serve as a releasable means for closing the notch only at the waistline, the balance of the notch or slit is nevertheless effectively sealed by means of the pocket. 40 The button 26 holds the inner portion of the pocket in proper position.

When the garment is to be taken off, the procedure is reversed, the buttons 18 being first disconnected; then access is had to the buttons 26 45 for the release of them. The trousers construction may then be readily withdrawn over the hips of the wearer.

I have made no reference to details of tailoring, because these details will be readily understood by those skilled in the art. Also, the garment 50 may obviously be made of any selected material; it may be lined either wholly or in part; and it may be provided with additional accessory pockets or other embellishments to suit different 55 requirements or desires.

In general, it will be understood that changes in the details, herein described and illustrated for

the purpose of explaining the nature of my invention, may be made by those skilled in the art without departing from the spirit and scope of the invention as expressed in the appended claims. It is, therefore, intended that these details be interpreted as illustrative, and not in a limiting sense.

Having thus described my invention, and illustrated its use, what I claim as new and desire to secure by Letters Patent is—

1. In a trousers construction, a waistband portion having a hip section and a waistband of smaller size than the hip section, said waistband being continuous across the front of the trousers, thereby providing a flyless front therefor, said waistband portion having a V-shaped notch at each side thereof extending upwardly through the waistband to facilitate passage over the hips of a wearer, a pocket for each of said V-shaped notches, each pocket having front and rear walls closed at their inner and bottom edges and substantially disconnected from each other along their outer and upper edges, the pockets being secured to and extending forwardly from said V-shaped notches to points adjacent the middle of the front of the trousers, means for detachably fastening the forward upper corner portion of each pocket to the waistband, and means for detachably fastening the edges of the waistband together at the V-shaped notches. 20

2. In a trousers construction, a waistband portion having a hip section and a waistband which is continuous across the front of the trousers, thereby providing a flyless front therefor, said waistband portion having notches at the sides thereof to facilitate passage over the hips of a wearer, a pocket for each of said notches comprising front and rear walls substantially disconnected from each other along their top and outer edges and connected along their inner and bottom edges, said outer edges being secured to the edges of said notch, respectively, the top edges of said pocket walls being spaced downwardly appreciably below the upper edge of the waistband portion for concealment thereby, the pockets extending forwardly from the notches to points adjacent the middle of the front of the trousers, means for detachably fastening the forward upper corner portion of each pocket to the waistband portion, and means for detachably fastening the edges of the waistband portion together at the notches, whereby release of the last-mentioned fastening means permits access to the first-mentioned fastening means to release the same. 40
